Fig. 5.

Fig. 6. 145

An exploded view diagram of a mechanical assembly. The diagram shows a central shaft with a threaded end. A lock washer (136) is positioned on the shaft, followed by a lock nut (135). A spring (133) is wound around the shaft, and a retaining ring (134) secures it. A sleeve (132) is slid onto the shaft, and a lock washer (137) is placed over the sleeve. A lock nut (138) is then secured onto the shaft. A retaining ring (139) is positioned on the shaft, and a lock washer (140) is placed over the retaining ring. A lock nut (141) is secured onto the shaft. A lock washer (142) is placed over the lock nut (141). A sleeve (143) is slid onto the shaft, and a lock washer (144) is placed over the sleeve. A lock nut (145) is secured onto the shaft. A retaining ring (146) is positioned on the shaft, and a lock washer (147) is placed over the retaining ring. A sleeve (148) is slid onto the shaft, and a lock washer (149) is placed over the sleeve. A lock nut (150) is secured onto the shaft. A retaining ring (151) is positioned on the shaft, and a lock washer (152) is placed over the retaining ring. A sleeve (153) is slid onto the shaft, and a lock washer (154) is placed over the sleeve.

UNITED STATES PATENT OFFICE.

CHARLES W. MUELLER, OF ST. LOUIS, MISSOURI, ASSIGNOR TO LEWIS INVISIBLE STITCH MACHINE CO., OF ST. LOUIS, MISSOURI, A CORPORATION OF MAINE.

INTERMITTENT-TENSION STITCH-FORMING MECHANISM.

Application filed February 14, 1924. Serial No. 692,696.

This invention relates to new and useful improvements in sewing machines generally, although more particularly to the stitch forming mechanism of blind stitch machines.

In blind stitch operations, particularly for joining a base layer and a superimposed layer of light weight material, it has heretofore been impossible to avoid the appearance of dimples or puckering in the "fair" side 10 of the base layer, owing to the fact that the stitches when set tight, cause the material to be pulled or drawn. If less tension were employed on the thread or threads, the dimples or puckering would be eliminated, but 15 the seam would be too loose for general practical requirements.

The principal object of my invention is to provide in a blind stitch sewing machine for joining a base layer and a superimposed 20 layer, an automatic intermittent tensioning mechanism for the thread or threads whereby certain of the stitches which penetrate the superimposed layer will be set under a tight tension, while the remaining stitches which 25 penetrate the superimposed layer and enter and emerge from the same face of the base layer will be set under a loose tension, thus creating a sufficiently tight seam to meet practical requirements, and at the same time 30 preventing the appearance of dimples or puckering on the "fair" side of the base layer.

Another object of the invention is to provide an intermittent plunger mechanism 35 wherein the plunger at predetermined intervals elevates the base layer into the path of reciprocation of the needle so as to insure certain of the stitches being made to penetrate the superimposed layer and enter and emerge from the same face of the base layer, and an intermittent thread tension release 40 mechanism, which is so timed as to permit the thread or threads of the stitches thus being formed to be loosely concatenated.

A further object of my invention resides 45 in the needle thread tensioning means whereby the thread when released will still be under sufficient tension to avoid the thread being pulled from the supply when the needle thread loop is being simultaneously shed from the hook and the slack is being taken up by the thread controller.

With the above and other objects in view which will more readily appear as the nature of the invention is better understood, 55 the same consists in the novel construction, combination and arrangement of parts hereinafter more fully described, illustrated and claimed.

In the accompanying drawings which illustrate one embodiment of my invention,

Figure 1 is a perspective view of the stitching head showing the application of my intermittent tension releasing mechanism. 65

Figure 2 is an end elevation of a machine embodying my invention.

Figure 3 is a detail vertical longitudinal sectional view showing the driving mechanism of the machine. 70

Figure 4 is a detail vertical transverse sectional view taken on the line 4—4 of Fig. 3.

Figure 5 is a top plan view of the stitching head.

Figure 6 is a detail horizontal sectional 75 view showing the intermittent tension releasing mechanism.

Figure 7 is an enlarged detail elevation of the releasing mechanism, showing the interchangeable actuating cams. 80

Figure 8 is a perspective view showing the various parts of the releasing mechanism in separated relation.

Figure 9 is an enlarged plan view of the seam produced by my invention. 85

Figure 10 is a sectional view of the seam taken on the line 10—10 of Fig. 9.

Figure 11 is a sectional view of the seam taken on the line 11—11 of Fig. 9.

Figure 12 is a detail vertical longitudinal sectional view showing the plunger and its actuating means, the feed dog, and the work clamp. 90

Figure 13 is a plan view of the presser foot showing the application of the fabric. 95

Figure 14 is an enlarged view, more or less diagrammatic showing the relative positions of the plunger, the fabric, and the needle when the superimposed layer only is being stitched. 100

Figure 15 is a similar view but showing the relation of the parts when the superimposed layer is being stitched to the base layer.

Figure 16 is a plan of the foot.

Figure 17 is a perspective view of the cradle.

Figure 18 is a longitudinal sectional view 5 of the base showing the means for supporting and depressing the work presenting mechanism.

Figure 19 is a diagrammatic view showing 10 the low position of reciprocation of the plunger, and

Figure 20 is a similar view but showing 15 the high position of reciprocation of the plunger.

Like reference numerals designate corresponding parts in all the figures of the drawings.

The sewing machine frame consists of a base 5 having at one end the work handling mechanism, a post 6 which extends upwardly 20 from the other end thereof and an overhanging arm 7 which is supported by the post and carries at its outer or free end a stitching head 8, said stitching head being disposed above the work handling mechanism.

25 The stitching head carries at its lower extremity a presser foot 9 for cooperation with the stitch forming and work handling mechanisms.

30 The operating parts carried by the stitching head 8 and the work handling mechanism carried by the base 5 are driven from a main shaft 10 which extends longitudinally in the overhanging arm 7 and is suitably journaled therein, said shaft having a hand 35 wheel pulley 11 fixed to the right hand end thereof.

The work handling mechanism which cooperates with the presser foot 9 includes a feed dog 12 and a work clamp 13. The feed 40 dog is of the 4-motion type, that is, it has a backward and forward movement and an up and down movement. The backward and forward movement of the feed dog is obtained through a rock shaft 14 which I term 45 the "feed travel" shaft and the up and down movement of the feed dog is obtained from a rock shaft 15 which I term the "feed lift" shaft. These rock shafts 14 and 15 extend longitudinally within the base 5 and have 50 their right hand ends journaled in bearings formed in a depending lug 16 and their left hand ends journaled in bearings formed in a block 17 detachably secured to the left hand end of the base 5 by screws 18-18.

55 Fixed to the outer end of the "feed travel" shaft 14 is a rock arm 19 and pivotally connecting the outer end of the rock arm and the forward extremity of the feed dog 12 is a link 20. The rock arm 19 extends in a

60 general vertical direction and the link 20 extends in a general horizontal direction, thus upon movement of the rock arm the link 20 will impart backward and forward movements to the feed dog 12. The feed 65 dog 12 is pivotally connected as at 21 to the

upper end of a substantially vertically disposed link 22, the lower end of said link being pivotally connected as at 23 to the horizontal arm 24 of a bell crank lever 25, the vertical arm 26 of said bell crank lever being pivotally connected as at 27 to one end of a link 28, the other end of said link 28 being pivotally connected as at 29 to the outer end of a vertically disposed rock arm 30 fixed to the "feed lift" shaft 15. In order 70 to maintain the feed surface of the feed dog in a substantially horizontal plane during the feeding movements thereof, I provide a spring 31 which is connected between a pin 32 on the link 22 and a pendent tail 33 fixed to the feed dog. It will, therefore, be observed that upon rocking movement of the shaft 15 the vertical link 22 will be bodily raised and lowered and consequently the feed dog will be given its up and down 75 movements. By proper timing of the shafts 14 and 15 a 4-way feed motion will be imparted to the feed dog.

The bell crank lever 25 is pivoted as at 34, and this pivot is fixed to a head 35 secured to the lower end of a guide post 36, said head and post forming a vertically movable carrier. The post 36 is mounted for vertical 80 sliding movements in a bore formed in the block 17, and this block is formed with a seat 37 for receiving and limiting the upward movement of the carrier. This carrier is normally held in its highest position by means of a flat spring 38 the inner end 85 of which is rigidly secured to the base 5 and the free end thereof is disposed under the carrier so as to yieldably hold the latter in its highest position. The upper end of the post projects above the block 17 and carries a 90 pair of rearwardly extending arms 39-39 between which is pivoted as at 40 the work clamp 13. From the foregoing, it will be observed that when the carrier is moved downwardly against the tension of the spring 38, both the feed dog 12 and the work 95 clamp 13 will be correspondingly moved, thus permitting the work presenting mechanism to be depressed as an entirety. In order to so depress the work presenting 100 mechanism, I have provided an operating lever 41 which is fulcrumed on the base 5 and has one end disposed in contact with the upper face of the head 35. The other end of the lever is adapted to be raised 105 through the application of a knee shifting device or treadle, neither of which however is shown in the drawings.

From the foregoing, it will be observed 110 that when the feed dog is elevated to its highest position, the fulcrum of the bell crank lever 25 is then shifted to the pivot 23 and consequently the last part of the rocking movement of the crank arm 30 will cause the bell crank 25 to be moved downwardly about its fulcrum 23 thus lowering 115 120 125 130

the work clamp 13. The parts are so timed that the work clamp is thus lowered prior to the feeding movement of the feed dog. The reverse order of movement will take place at substantially the time when the feed dog reaches the end of its feeding stroke, thus causing the clamp to engage the fabric and clamp the latter against the foot prior to the time the feed dog begins its downward movement.

In order to rock the "feed travel" shaft 14 and the "feed lift" shaft 15 I provide the main shaft 10 with eccentrics 42 and 43 respectively. A connection rod 44 has its upper end engageable with the eccentric 42 and its lower end pivotally connected as at 45 to a rock arm 46 fixed to the rock shaft 14. A connection rod 47 has its upper end engageable with the eccentric 43 and its lower end pivotally connected as at 48 to a rock arm 49 fixed to the shaft 15. It will be noted that the connection rods 44 and 47 are disposed within the post 6 of the machine frame.

25 The fabric as it is fed past the stitching head is adapted to be intermittently crimped or bent so as to form a node which will be positioned in the path of the needle whereby the latter will, or will not, depending upon 30 the height of the node, enter said node and project a penetrant needle thread loop therethrough, as will hereinafter be more fully described. In order to provide for this crimping or bending action of the material, 35 the presser foot 9 is formed with an opening 50. The material is upwardly bent or crimped into this opening by means of a reciprocatory plunger 51 which extends upwardly through the feed dog 12 and work 40 clamp 13. This plunger is mounted for vertical sliding movements within a barrel 52 fitted within a bore 53 formed in the end block 17. The lower end of the plunger 51 is formed with a reduced end 54 forming a 45 resultant shoulder 55. The lower end of the barrel 52 is fixed to a lug 56 and the reduced end 54 of the plunger extends through an opening 57 formed in said lug and threaded onto the lower projecting end thereof are 50 lock nuts 58. Disposed within the barrel 52 between the shoulder 55 of the plunger and the lug 56 is a coil spring 59 which yieldably holds the plunger in its highest 55 position relative to the lug 56. It will be evident that when the barrel is moved upwardly the plunger will be moved therewith, but just as soon as the plunger engages the fabric a resistance to the upward movement of said plunger will take place and the spring 59 will permit the barrel to continue its movement while the plunger spring 59 is being compressed.

60 The plunger 51 is vertically reciprocated through the medium of a rock shaft 60 which extends longitudinally of the base 5.

The rock shaft 60 is provided with a crank arm 61 which is connected by a link 62 to the lug 56. The rock shaft 60 is located below the plunger and the link 62 extends substantially vertically when the plunger is at its highest position.

For the purpose of bodily varying the vertical position of reciprocation of the plunger, I have supported the rock shaft 60 for vertical bodily movements and to this end I have journaled the shaft in bearings formed in a cradle or rocking frame which I have designated as a whole by the reference numeral 63. This cradle includes a rock shaft 64 having one end supported for 65 rocking movements on a pin 65 carried by the end wall of the base 5 and its other end journaled in the depending lug 16 of said base. The rock shaft 64 is provided with downwardly and rearwardly extending rock arms 66-66 in which the plunger rock shaft 60 is journaled. The rock shaft 64 of the cradle is provided adjacent its right end with a laterally and longitudinally extending rock arm 67 having forwardly extending arms 68-68. Disposed between the arms 68-68 is a sleeve 69 forming a slide bearing for the lower end of a vertically disposed cam roller shaft 70. The sleeve 69 is supported on the arm 68-68 by horizontally disposed pivot pins 71-71. Fixed to the sleeve 69 is a face cam 72 and this cam is formed on its upper face with a curved surface containing diametrically opposed high points 73-73 and diametrically opposed low points 74-74. The cam roller shaft 70 extends upwardly through the post 6 of the frame and is driven from the main shaft 10 by a gear coupling 75 which reduces the speed of rotation of the cam roller shaft 70 relative to the main shaft 10 by the ratio 1 to 4. This gear coupling 75 includes a spiral gear 75^a which is fixed to the cam roller shaft 70 through the medium of a collar 75^b and a spiral gear 75^c which is fixed to the main shaft 10. The cam roller shaft extends through a concentric opening in the cam 72 and fixed to the shaft directly above the cam face of said cam is a sleeve 76 which carries a cam roller 77 engageable with the cam face of the cam. The upper end of the cam roller shaft 70 above the gear coupling 75 is mounted within a sleeve 78 which has threaded engagement with an opening formed in a plate 79 which is detachably secured to the upper end of the frame. The lower end of the sleeve rests on the collar 75^b of the gear coupling. Fixed to the upper end of the sleeve 78 is a knurled head 80 by means of which the vertical position of the sleeve may be adjusted. A screw 81 is threaded into the upper end of the cam roller shaft 70 and the head of this screw bears against the upper end of the sleeve 78 and thereby retains the cam roller shaft 70.

against downward movement relative to the sleeve 78. In other words, the collar 75^b prevents upward movement of the cam roller shaft 70 relative to the sleeve 78, and the screw 81 prevents downward movement of the cam roller shaft relative to said sleeve. Thus upon vertical movement of the sleeve 78, the cam roller shaft 70 will be correspondingly moved. Downward movement of the cam roller shaft 70 causes the cradle 63 to be rocked through the medium of the roller 77, thus elevating the plunger shaft 60, the latter being moved upwardly in an arc about the pivot of the cradle. The upward bodily movement of the shaft 60 will in turn bodily elevate the position of reciprocation of the plunger through the medium of the rock arm 61, link 62 and lug 56, as diagrammatically shown in Figure 20. Upward adjustment of the cam roller shaft 70 will lower the position of the shaft 60 as diagrammatically shown in Figure 19.

The plunger shaft 60 is rocked in the supporting cradle or frame 63 by the rock arm 49, the outer end of which is pivotally connected as at 49^a to the upper end of a substantially vertically disposed link 49^b, the lower end of the link being pivotally connected as at 49^c to a rock arm 60^a fixed to the plunger shaft 60. Inasmuch as the cam 72 is provided with two high points and two low points, and the main shaft makes four complete revolutions to one of the cam roller shaft 70, it follows that the bodily position of reciprocation of the plunger will be elevated during every other revolution of the main shaft, and that the plunger will be reciprocated when the plunger rock shaft 60 is in its "high" position and also when it is in its "low" position.

The plate 79 is slotted to form a clamp for the sleeve 78, and a screw 79^a cooperates with the clamp to lock the sleeve against turning. In order to turn the sleeve it is necessary to first release the clamp. The proper bodily position of reciprocation of the plunger may then be obtained by actuating the sleeve 78 after which the sleeve is clamped against further free rotation by the screw 79^a, thus permanently fixing or setting the bodily position of reciprocation of the plunger.

In order to control the depth of needle penetration in the superimposed fabric, I have provided a coil sprng 82 which is disposed between the front wall of the base 5 of the frame and a rock arm 83 fixed to the cradle 63. The rock arm 83 is formed with a rectangular slot 84 and disposed in this slot is an angular sleeve 85 having a threaded bore 86. An adjusting bolt 87 passes through the front wall of the base 5, through the coil spring 82 and has its inner end engaged with the threaded opening 86 of the sleeve 85. Fixed to the outer end of the bolt 87 is a knurled head 88 which bears against

the front wall. The rear end of the angular sleeve 85 is provided with flanges 89-89.

The machine as illustrated, is particularly adapted for making blind stitch felling seams whereby the edge portion of a superimposed layer of material is secured to a base layer without displaying any of the stitching thread upon the lower or "fair" side of the base layer. I have illustrated such seam in Figures 9, 10 and 11 of the accompanying drawings. In these drawings, the fabric is indicated generally by the numeral 90 and includes a base layer 91 and a superimposed layer 92, the latter being in this case an integral part of the base layer 80 and forming a hem or fell. The marginal edge portion of the superimposed layer 92 is provided with a binding 93 and this binding is secured to the superimposed layer by a line of through-and-through stitches 94. The superimposed layer 92 is secured to the base layer 91 by a line of stitches all of which penetrate the superimposed layer. At intervals, preferably regular intervals, for regular spacing thereof, certain of the 90 stitches which penetrate the superimposed layer 92 also pass into and out of the upper face of the base layer 91. The stitches which penetrate the superimposed layer only are tightly set whereas those stitches which also pass into and out of the upper face of the base layer are loosely set. As a result, a sufficiently tight seam for all practical purposes is created and the formation of dimples or puckers on the under or "fair" side of the base layer will be prevented. These stitches are preferably formed through the instrumentalities of a needle 95 and a co-operating hook 96^a, the latter being shown in Fig. 1 of the drawings. The needle 95 is 105 curved and oscillates about a horizontal axis disposed directly above the point of entrance of the needle in the fabric. The needle oscillates in a vertical plane disposed at an angle to the general line of the seam and in this instance I have shown the needle as being disposed at an angle of 45°. The needle enters the superimposed layer 92 at a point adjacent the line of stitches 94 and under the marginal edge of the binding which is 110 secured by said stitches 94. The needle thread 96 is formed into a series of loose penetrant loops 97 and also into a series of tight penetrant loops 98, the latter being alternately disposed with respect to the loops 115 97. The loops 97 pass through the superimposed layer 92 and thence into and out of the upper face of the base layer 91, and the bite of each loop projects above the face of said base layer. The loops 98 do not pass into the base layer 91 but preferably terminate between the upper and lower faces of the superimposed layer 92. These loops are keyed, that is locked, by a bobbin thread 99. The specific seam above described forms the 120 125 130

subject matter of my copending application Ser. No. 685,174 filed January 9, 1924.

The presser foot 9 is rigidly but detachably secured to the head 8 by means of screws 100-100. This foot is, of course, disposed directly above the feed dog 12 and the work clamp 13 and the foot is formed with the opening 50 to receive the node of fabric formed by the plunger 51. The horizontal axis of the needle 95 is disposed directly above and in alignment with the longitudinal axis of the plunger 51. The opening 50 is a part of a centrally disposed and rearwardly extending fabric guiding slot 102, which extends in the line of feed to a point beyond the plunger 51, the rear or inner end of the guiding slot 102 terminating in rear of the plunger 51 in an offset portion 103. A needle guide 104 which is formed of hardened steel is detachably secured to the foot by a screw 105 and this guide is formed with a guiding recess 106 for the needle 95. This guide is attached to that portion of the foot on the right-hand side of the fabric guiding slot 102 and one end thereof terminates in a combined edge guide and lifting device 107. This combined edge guide and lifting device 107 is employed for the purpose of engaging the margin of the binding 103 and elevating the marginal edge thereof above the path of the needle whereby the latter may penetrate the superimposed layer 92 at a point close to the line of through-and-through stitches 94, thus permitting the marginal edge portion of the body to ultimately cover or conceal the connecting needle thread 96. Secured to the left hand side of the presser foot by a screw 108 is a shelf 109 which serves to support the marginal edge portion of the superimposed layer 92 above the path of the needle thereby preventing the needle from penetrating the superimposed layer except at the original point of entrance, viz: adjacent the marginal edge of the binding. The shelf 109 furthermore supports the superimposed layer 92 above the path of reciprocation of the plunger 51 so that said plunger does not at any time engage said superimposed layer 92.

The needle 95 is centrally carried by a yoke shaped needle bar 110 pivoted as at 111 at the extremities of its limbs on the head 8. One of the needle bar limbs has a lever prolongation and this lever prolongation is pivoted to the lower end of a link 112 with a wrist pin 113 of a counterweighted crank arm 114 carried by a jack shaft 115 which is journaled in the head 8 and is operated from the main shaft 10 by a 1-to-1 gear coupling 115^a. The axis of the needle bar is disposed at an angle of 45° relative to the line of feed and consequently the needle will oscillate in a vertical plane disposed at an angle of 45° to the line of feed. In as-

much as I employ a 1-to-1 gear coupling 115^a, the needle will make one complete oscillation to every rotation of the main shaft 10. The needle cooperates with the hook 96^a to form a series of lock stitches. This hook is mounted on the shaft 116 and this shaft is driven in a 2-to-1 relation relative to the rotation of the jack shaft 115 through the medium of beveled gears 117, vertical shaft 118 and spiral gear coupling 119, the gears 75 of which coupling are respectively carried by the jack shaft 115 and the vertical shaft 118. Thus the hook will be rotated twice for each oscillation of the needle and will cooperate with the needle in a manner well known to those skilled in this art.

A take-up arm 120 for the needle thread is fixed to a sleeve or hub 121 which is journaled on a horizontal pin 122 in the head 8. A rock arm 123 is also fixed to the sleeve or hub 121 and has sliding engagement with a block 124 which is pivotally connected as at 125 to a laterally extending rigid arm 126 of the link 112. The take-up arm 120 is thus given a differential rate of motion in an 90 appropriately timed relation to the needle oscillations. In the cyclic operation, the take-up lever is given a rapid rise, a slow descent and an extended dwell in its lowered position.

The needle thread 96 is led from the supply to a stationary thread guide 127 fixed to the head 8, thence through tension disks 128 and 129 respectively of an intermittent tension device, through a stationary guide 130, 100 thence through the spring tension 131, thence through a guide 132 formed in the end of the take-up arm 120 and thence to the needle 95.

The intermittent tension device acts on 105 the needle thread 96 so as to form alternately tight and loose stitches as hereinbefore described. The tension disks 128 and 129 are mounted on a horizontal rod 133 mounted to slide longitudinally in a bore 134 110 formed in the head 8. This rod is preferably held against rotary movement, however, by a screw 135 having threaded engagement with the head 8 and operating in a longitudinal groove 136 formed in said rod. 115 Formed on the front end of the rod 133 is a flange or shoulder 137 and the two disks 128 and 129 are disposed between the frame 8 and said flange 137. The front end of the rod is threaded and is provided with a nut 138. Between the disk 129 and the nut 138 is a light coil spring 139. The rod 133 extends rearwardly of the frame 8 and is formed with a threaded end portion 140 having a nut 141 threaded thereon. Interposed between the frame 8 and the nut 141 is 125 a heavy coil spring 142 which has considerably more tensional strength or pressure than the spring 139. The spring 142 urges the rod 143 rearwardly and causes the flange 130

or shoulder 137 to force the disks against each other and against the frame 8. Thus in the normal position of the parts, the needle thread is under the heavy tension of the spring 142, and the light spring 139 has practically no effect on the thread. The rod 133 is adapted to be moved forwardly so as to relieve the disks of the heavy pressure exerted by the spring 142, but permits the 10 spring 139 to still exert its light tension against said disks and needle thread passing therebetween. In order to intermittently actuate the rod 133 and thereby intermittently control the tension, I have formed the 15 vertical hook shaft 118 with a worm 143 which drives a horizontally disposed shaft 144 through the medium of a worm 145 formed on said shaft 144. The shaft 144 is journaled in the head 8 and is provided at 20 its end with a surface cam 146 having a single high point 147 adapted to cooperate with the end of the tension rod 133 and move the latter longitudinally to release the tension disks from pressure of the heavy spring 142. 25 The gear connection 143 and 145 for the cam shaft 144 is such that the high point 147 will actuate the tension rod 133 during alternate oscillations of the needle. Immediately following the casting off of the needle thread 30 loop from the point of the hook 96^a the take-up arm 120 begins its upward movement for the purpose of taking up slack in said needle thread and thereby setting the stitch. In view of the fact that the cam 147 actuates 35 the tension release during the setting of every other stitch, it follows that the alternate stitches will be loosely and tightly set.

Occasionally it may be desired to form a 40 seam in which all of the stitches are loosely set. To this end I have provided the shaft 144 with a surface cam 148 which is disposed adjacent the cam 146. The surface cam 148 is provided with a diametrically opposed high points 149—149. The shaft 144 is 45 adapted to be shifted endwise so as to position either of the cams 146 or 148 into engagement with the tension rod 133. In order to retain the shaft 144 in either of its 50 previously mentioned set positions, I have provided a hook-shaped latch 150 which is pivoted at 151 to the head 8, the latch being adapted to engage in either of the peripheral 55 grooves 152 and 153 formed in the shaft 144. The grooves 152 and 153 are spaced apart a distance equal to the distance between the centers of the cams 146 and 148. As a result, when the latch 150 is positioned 60 in the groove 152, the cam 146 will be located in cooperative relation to the tension rod 133, and when the latch 150 engages in the groove 153, the cam 148 will be located in cooperative position to the tension rod 133. The worm 145 which is fixed to the 65 shaft 144 is of a length sufficient to permit of this endwise adjustment of the rod 144 with-

out disconnecting said worm from its driving connection. Therefore, when the cam 148 is positioned to cooperate with the tension rod 133, the diametrically high points 149—149 will automatically release the tension during the setting of all stitches. Thus the seam will be formed of stitches which are each set loosely.

In the operation of the machine, the fabric is positioned in proper sewing relation 75 relative to the presser foot as illustrated in Figures 1 and 13, the edge portion of the super-imposed layer 92 being guided within the channel 102 of the presser-foot, the extreme edge portion which is covered by the 80 binding 93 being held above the plunger and out of engagement therewith by means of the shelf 109 of the presser-foot. The marginal edge portion of the binding 93 is slightly elevated by the lifting device 107 85 which is attached to the presser-foot. This lifting device serves to lift the marginal edge portion of said binding so as to permit the needle point to enter thereunder and close to the line of the through-and-through 90 stitches 94. Inasmuch as the superimposed layer is supported above the path of the needle reciprocation by means of the shelf 109, the needle will always penetrate said superimposed layer. It is desirable to have 95 the needle alternately penetrate the base layer 91 and this is accomplished by means of the plunger 51 which causes said base layer to be alternately crimped for penetration by the needle during alternate reciprocations thereof. This alternate crimping 100 or bending of the base layer 91 is brought about by the following:—

When either of the high points 73 of the cam 72 is engaged by the roller 77, the 105 cradle 63 will be rocked thus elevating the plunger rock shaft 60. The highest position of the plunger rock shaft 60 through the medium of the high points 73 above noted, determines the position of the base layer 110 relative to the path of needle travel. Therefore, this determines the depth of needle penetration in the base layer. The cam 72 is cut so as to produce an extreme limit of movement for adjustment of the bodily 115 position of reciprocation of the plunger, thus providing a plunger mechanism which will take care of fabrics of different weights. As the cam roller 77 leaves the high point of the cam and approaches 120 the low point 74 thereof the cradle 63 will be returned, that is, rocked, through the action of the coil spring 82 and the cam will tend to move upwardly and maintain its contact relation with the roller 125 77. This upward movement of the cam due to the rocking movement of the cradle 63 necessarily lowers the plunger rock shaft 60 and consequently the lowest vertical position 130 of reciprocation of the plunger is obtained.

This extreme low position, however, may be easily regulated through the medium of the rod 87 and the sleeve 85 which engage with the rock arm 83 of the cradle and thereby

- 5 variably limit the return rocking movement of the cradle 63. By this means the low points 74 of the cam are held from intermittent contact with the roller 77, said roller during each rotation of the cam roller shaft
- 10 70 intermittently engaging the high points 73 only of said cam. Consequently the high points 73 of the cam will through the mechanism described cause the material to be upwardly crimped and positioned in the path
- 15 15 of reciprocation of the needle. Thus when each high point 73 of the cam engages the cam roller 77 the base layer 91 is upwardly crimped and positioned in the path of reciprocation of the needle, the needle thus
- 20 20 penetrating not only the superimposed layer but also entering and emerging from the same face of the base layer. This stitch is loosely set due to the action of the intermittent tension releasing mechanism. The
- 25 25 fabric is then fed rearwardly a distance equal to the length of one stitch and the needle in its next movement penetrates only the superimposed layer 92, the needle escaping the base layer by reason of the high point 73 of
- 30 30 the cam leaving the cam roller, and the rocking movement of the cradle 63 being limited by the proper adjustment of the rod 87. Thus the plunger is elevated during every other cycle, that is, during the formation of every
- 35 35 other stitch. The parts are so timed that when the needle thread of the stitch which penetrates the superimposed layer 92 only is being cast from the hook, the cam 147 of the tension release is ineffective and consequently the stitch is tightly set.

It is of course to be understood that the details of structure and arrangement of parts may be variously changed and modified without departing from the spirit and scope of my invention.

I claim:

1. In a sewing machine, the combination with a reciprocatory threaded needle and a complemental stitch forming mechanism for forming a series of connected stitches, said mechanism including a rotary hook and a threaded bobbin, of means for rotating said hook, a tension device for the needle thread, and means respectively releasing and restoring said tension device automatically during the formation of alternate stitches whereby said connected stitches will be alternately set loose and tight.

2. In a sewing machine, the combination with a reciprocatory threaded needle and a complemental stitch forming mechanism, for forming a series of connected stitches, of a tension device for the needle thread, including relatively weak and strong pressure springs, the strong pressure spring normally

serving to tension the needle thread, and means for respectively releasing and restoring said strong pressure spring during the formation of alternate stitches whereby said connected stitches will be alternately set 70 loose and tight.

3. In a blind stitch sewing machine, the combination with a reciprocatory threaded needle operating in a constant path and a complemental stitch forming mechanism for 75 forming a series of connected stitches, of a work presenting mechanism operating below said stitch forming mechanism, a vertically movable plunger operating below the work material, means for moving the plunger upwardly to bend the material in advance of and for alternate needle penetrations, a tension device for the needle thread, and means for automatically releasing said tension device in timed relation only to said 80 alternate needle penetrations.

4. In a blind stitch sewing machine, the combination with a reciprocatory threaded needle operating in a constant path and a complemental stitch forming mechanism for 85 forming a series of connected stitches, of a work presenting mechanism operating below said stitch forming mechanism, a constantly reciprocatory plunger operating below the material, means for bodily elevating the 90 plunger without disturbing its reciprocatory movements to bend the material in advance of and for alternate needle penetrations, a tension device for the needle thread, and means for automatically releasing said tension device in timed relation only to said 95 alternate needle penetrations.

5. In a sewing machine, the combination with a frame having a bore, of a rod mounted in said bore for relative longitudinal movements and provided with a shoulder, of a pair of tension discs mounted on the rod between the shoulder and the frame, a spring interposed between the frame and the rod for yieldingly clamping said discs between 100 the frame and the shoulder of the rod, means for intermittently moving said rod against the tension of said spring to release said discs, predetermined adjustable means for intermittently moving said rod against the tension of said spring comprising a longitudinally adjustable cam-shaft, a plurality of differently timed cams carried thereby and respectively adapted for engagement with the end of said rod in different positions of adjustment of said cam-shaft, and means for retaining said shaft in an adjusted position.

6. In a sewing machine, the combination with a frame having a bore, of a rod mounted in said bore for relative longitudinal movements and provided with a shoulder, of a pair of tension discs mounted on the rod between the shoulder and the frame, a 115 spring interposed between the frame and the 120

rod for yieldingly clamping said discs between the frame and the shoulder of the rod, means for intermittently moving said rod against the tension of said spring to release said discs, predetermined adjustable means for intermittently moving said rod against the tension of said spring, comprising a longitudinally adjustable cam-shaft, a plurality of differently timed cams carried thereby and respectively adapted for engagement with the end of said rod in different positions of adjustment of said cam-shaft, said shaft being formed with spaced annular recesses, and means for retaining said shaft in an adjusted position comprising a keeper pivoted on the frame and engageable in a registering recess.

7. In a blind stitch felling machine, the combination with a reciprocatory threaded needle operating in a constant path and a complementary stitch forming mechanism for forming a series of connected stitches, of a work presenting mechanism including a presser foot having means for supporting the fell above the base layer, whereby the needle will penetrate said fell during each reciprocation, means for elevating the base layer into the path and in advance of only alternate needle reciprocations whereby said needle will alternately penetrate the fell and the fell and base layer, a tension device for the needle thread, and means for automatically releasing said tension device during the formation of each stitch penetrating the base layer.

8. In a blind stitch sewing machine for felling seams, the combination with a reciprocatory threaded needle and a complementary stitch forming mechanism for forming a series of connected stitches, of a presser foot disposed below said needle and comprising a body portion having a rearwardly extending slot for guiding a previously bound fell, and an edge lifting device secured to the body portion for raising the marginal portion of the binding for permitting the needle to pass through the fell directly under the raised portion of the binding, a feeding mechanism cooperating with the foot to feed the material past said stitch forming mechanism, a vertically movable plunger operating below the presser foot, means for moving the plunger upwardly to bend the body fabric in advance of and for predetermined needle penetrations whereby the needle during one reciprocation will enter the fell only and during another reciprocation will enter both the fell and the body fabric, a tension device for the needle thread, and means for releasing and restoring said tension device automatically during the formation of the stitches whereby predetermined connected stitches will be set loose and tight respectively.

9. In a blind stitch sewing machine for fell-

ing seams, the combination with a reciprocatory threaded needle and a complementary stitch forming mechanism for forming a series of connected stitches, of a presser foot disposed below said needle and comprising a body portion having a rearwardly extending slot for guiding a previously bound fell, and an edge lifting device secured to the body portion for raising the marginal portion of the binding for permitting the needle to pass through the fell directly under the raised portion of the binding, a feeding mechanism cooperating with the foot to feed the material past said stitch forming mechanism, a vertically movable plunger operating below the presser foot, means for moving the plunger upwardly to bend the body fabric in advance of and for predetermined needle penetrations whereby the needle during one reciprocation will enter the fell only and during another reciprocation will enter both the fell and the body fabric, a tension device for the needle thread, and means for automatically releasing said tension during the formation of the stitches connecting the fell and the body fabric and for automatically restoring the tension during the formation of the stitches passing through the fell only.

10. In a blind stitch sewing machine for felling seams, the combination with a reciprocatory threaded needle and a complementary stitch forming mechanism for forming a series of connected stitches, of a presser foot disposed below said needle and comprising a body portion having a rearwardly extending slot for guiding a previously bound fell, and an edge lifting device secured to the body portion for raising the marginal portion of the binding for permitting the needle to pass through the fell directly under the raised portion of the binding, a feeding mechanism cooperating with the foot to feed the material past said stitch forming mechanism, a vertically movable plunger operating below the presser foot, means for moving the plunger upwardly to bend the body fabric in advance of and for alternate needle penetrations whereby the needle during one reciprocation will enter the fell only and during the next reciprocation will enter both the fell and the body fabric, a tension device for the needle thread, and means for respectively releasing and restoring said tension device automatically during the formation of alternate stitches whereby said connected stitches will be alternately set loose and tight.

11. In a blind stitch sewing machine for felling seams, the combination with a reciprocatory threaded needle and a complementary stitch forming mechanism for forming a series of connected stitches, of a presser foot disposed below said needle and comprising a body portion having a rearwardly ex-

tending slot for guiding a previously bound fell, and an edge lifting device secured to the body portion for raising the marginal portion of the binding for permitting the 5 needle to pass through the fell directly under the raised portion of the binding, a feeding mechanism cooperating with the foot to feed the material past said stitch forming mechanism, a vertically movable plunger operating 10 below the presser foot, means for moving the plunger upwardly to bend the body fabric in advance of and for alternate needle penetrations whereby the needle during one re-

ciprocation will enter the fell only and during the next reciprocation will enter both the 15 fell and the body fabric, a tension device for the needle thread, and means for automatically releasing said tension during the formation of the stitches connecting the fell and the body fabric and for automatically restoring the tension during the formation of 20 the stitches passing through the fell only.

In testimony whereof I hereunto affix my signature.

CHARLES W. MUELLER.
